Primary Examiner — Patrick A Palasik

(74) Attorney, Agent, or Firm — George A. Leone; Citadel Patent Law

(57) **CLAIM**

The ornamental design for a extruded structural building component for robotics, as shown and described.

DESCRIPTION

FIG. 1 is a perspective view of an extruded structural building component for robotics showing my new design; FIG. 2 is a top side elevational view thereof, the bottom side view being substantially identical;

FIG. 3 is a left side elevational view thereof, the opposite side being substantially identical;

FIG. 4 is a bottom plan view thereof; and,

FIG. 5 is a top plan view thereof.

The article is shown with a symbolic break in its length. The appearance of any portion of the article between the break lines forms no part of the claimed design. The claimed extruded structural building component for robotics is used for constructing robotic structures, base frames and the like, for example.

Any broken line illustration of environmental structure in the drawing is not part of the design sought to be patented.

Note: The use of separation and a bracket indicates that the

precise length is not claimed.
